UNITED STATES PATENT OFFICE.

CHARLES HEATH, OF FORT WORTH, TEXAS.

WELL BARREL.

Application filed August 31, 1927. Serial No. 216,671.

This invention relates to working barrels for oil wells.

It is a well known fact that where conditions are normal, that the 2" by 6' working barrel having either canvas or leather cups constitutes the best means for pumping oil from the earth; but where sand and gas pressure are encountered, the use of this barrel has proven too expensive because of 10 the pulling operations necessitated.

It is to overcome this objection that this invention is designed and a primary object thereof is to so construct such a barrel that it will operate as a gas trap permitting the 15 fluid to run in and prevent the gas from working on the valves, thereby effecting a great saving to the producer.

Another object is to construct the barrel so that if sand enters with the fluid the 20 greater portion of it will be trapped and thus prevented from sticking any of the valves.

In carrying out these objects the invention is susceptible of a wide range of modifications without departing from the spirit or sacrificing any of the advantages of the 25 claimed invention; there being shown in the drawings for illustrative purposes a preferred and practical form, in which:—

30 Figure 1 is a longitudinal section with parts in elevation of a well barrel constructed in accordance with this invention.

Figure 2 is an enlarged detail section of the upper end of the barrel indicated by 35 the line 2 in Fig. 1,

Figures 3 and 4 are similar views showing successive portions of the barrel and indicated by the lines 3 and 4 of Fig. 1.

40 Figure 5 is a similar view of the next succeeding portion of the barrel with a portion of the working valve in section, this figure being indicated by the line 5 of Fig. 1,

Figure 6 is a vertical section of a continuation of the portion shown in Fig. 5, showing the remainder of the working barrel and the improved standing valve connected therewith, together with the bottom of the barrel which is to be connected with the well tubing and indicated by the line 6 in 45 Fig. 1,

Figure 7 is a transverse section taken on the line 7—7 of Fig. 2,

Figure 8 is a similar view taken on the line 8—8 of Fig. 2, and

55 Figures 9 and 10 are transverse sections

taken respectively on the lines 9—9 and 10—10 of Fig. 6.

This working barrel is designed to be connected at its upper end with the well tubing shown at T in Fig. 1, and at its lower end with anchoring tubes, not shown, and is composed of a tubular connection 1 internally threaded at its upper end for connection with the tubing T and exteriorly threaded at its lower end for connection with

a tubular steel outer shell section 10 which latter is detachably united by a coupling 20 in the form of a steel sleeve or collar, with a steel pipe or outer shell section 30. These sections 10 and 30 are preferably of

70 the same shape and size as shown in Fig. 1, said collar 20 being also of the same size.

The connector 1 has a rope socket neck 2 at its upper end and its lower end is enlarged and offset outwardly, as shown at 3, the inner face of said enlargement being beveled or inclined outwardly as shown at 4, to provide space to receive the upper end of a valve protecting casing 15 in which is housed the upper portion of the valve stem 5. This valve stem 5 extends above the reduced neck 16 of the casing 15 and is provided with an enlargement or head 6 having a shoulder 7 at its lower end which is

80 designed to rest on the upper edge of the neck 16 to seat stem 5, it being understood that when the pump is in operation the stem 5 works up and down in the casing 15. The stem 5 is threaded at its upper terminal as shown at 8, for connection with the well

85 rods, not shown. The stem 5 also has an enlargement or head 5^a near its lower end for a purpose presently to be described.

90 The casing 15 extends through and is held in position within the shell 10 by a guide member 11 provided with a plurality of apertures 12 for a purpose hereafter to be described. This casing 15 is provided at its upper end below said guide 11 with a plurality of openings 17, twenty of which 95 are preferably used, and which permit the outflow of the oil therefrom, as will be presently described. The casing 15 has its lower end tapered as shown at 18 and designed to fit tightly within a correspondingly 100 shaped socket 24 formed in the upper end of the collar 20 and which is held in said collar by friction. The casing 10 has threaded connection with the upper end of the collar or coupling 20 as shown clearly in Fig.

105

110 Figures 9 and 10 are transverse sections

3, and on the lower end of said collar is threaded the casing 30 which forms substantially a continuation of the casing 10. A cast iron working barrel 25 has its upper end exteriorly threaded and engaged with the inner face of the lower end of collar 20, as is shown clearly in Fig. 3. This barrel extends down through the outer shell or casing 30 and is spaced radially therefrom and is connected at its lower end with a steel standing valve 50 which will be presently described in detail.

The valve stem 5 also extends through the protective casing 15 and the working barrel 25 and is connected at its lower end with the working valve 60, said valve being shown provided with a threaded extension 61 at its upper end with which an internally threaded socket 26 on the stem 5 is engaged.

The outer shell 30 is provided at its upper end adjacent its connection with the coupling 20 with a plurality of openings 31 which are designed to permit the inflow of the oil from the well into said casing from which it will be conducted to the upper portion of the well in a manner presently to be described.

The steel standing valve 50 which is connected with the lower end of the outer shell 30 has a tubular central extension 51 which fits in a socket 41 located centrally within the bottom barrel section 40, which is threaded to the lower end of the valve 50.

Two steel standing valves 52 and 53 of similar construction are arranged longitudinally of the valve member 50, as shown clearly in Fig. 6, including ball valves 54 designed to be seated on the upper ends of the cylindrical valves 52 and 53. A plurality of conduits or passages 56 extend longitudinally through the body of the valve 50 to permit the oil to pass down through the valve to the chamber 57 in the bottom thereof and from which it flows up through the steel standing valves 52 and 53 into the chamber 58 above them and passes through openings 59 in the inner walls of said chambers to the interior or central passage 59^a of valve 50.

The barrel section 40 which is connected to the lower end of the valve 50 is preferably provided with tapering walls, as shown at 42, which merge at their lower ends into a threaded neck 43 designed to be connected with anchoring tubes, not shown.

The working valve 60 which constitutes an essential feature of the invention is housed within the cast iron working barrel 25 and comprises the usual tubular body member 62 having mounted thereon the usual cups 63, five of which are usually employed, one only being shown in the drawings. This body is also equipped with the usual collars 64, four of which are used. A lock nut 65

connects the tubular body portion 62 with an enlarged section 66 which has a valve chamber 67 formed therein, closed by a ball valve 68 seating on an annular seat 69 secured between the section 66 and another section 70, which has threaded engagement with the section 66, as is shown clearly in Fig. 6. The section 70 has a coil spring 71 located in a recess 72 formed in the outer face of said section, said spring projecting beyond said face and designed to prevent the passage of any sand between it and the cast iron barrel 25. This spring is preferably constructed of spring steel which is ground inside and out after hardening, to ensure a smooth seat. Connected with the upper end of the body member 62 is another tubular section 73 which is also provided with a spring 74 similar in construction to the spring 71 and designed for the same purpose, that is, to prevent the passage of sand between it and the barrel 25. A section 75 is threadedly connected with the upper end of section 73, as shown in Fig. 5, and has detachably mounted on its upper end, a section 76 which carries the reduced threaded neck 61 which is detachably engaged with the socket 26 on the valve stem 5.

These springs 71 and 74 prevent all possibility of any sand which might be drawn up into the barrel 25 from coming in contact with the cups 63 and hence a great saving is effected in the pulling of the valves, which is usually necessary and which is very expensive.

This working valve 60 includes the old five cup valve structure but operated under different conditions, working within a cast iron barrel 25 instead of a steel barrel which permits the use of the steel springs 71 and 74 to be used one above and one below the cups, preventing all possibility of any sand passing them, and which eliminates the pulling expense and loss of production.

The steel valve protector 15 which works over the valve stem 5 is designed to be lifted to the top of the tubing with the valve stem and when running the rods, not shown, back in the tubing, the casing 15 fits the tubing so closely that if the rods should be accidentally dropped and there is fluid in the hole, it will prevent the rods from hitting the barrel hard enough to separate the tubing. It also prevents any foreign substance that might get into the top of the tubing from entering any of the valves and requiring the tubing to be pulled. This barrel also constitutes a gas trap since the entrance of the fluid at the top of the barrel runs in instead of being sucked in as in the old construction and this running in of the fluid prevents the gas from working on the valves.

In the operation of this barrel the parts being shown connected as in Fig. 1, the oil from the well enters the casing 30 through

the openings 31 and flows down through said casing through the openings 56 in the standing valve 50 to the chamber 57 at the bottom thereof. From this chamber the oil passes 5 up through the valves 52 and 53 into chamber 58 and through the openings 59 to the center of valve 50 passing upwardly through the bore 59^a thereof into the working valve 60 from whence it passes to the cast iron 10 barrel 25 and up through the casing 15 and out of the apertures 17 thereof into the casing 10 from whence it passes through the openings 12 in the guide 11 up through the member 1 and out of the tubes, not shown.

15 In this passage of the oil any sand which may enter with it through the openings 31 into the casing 30 drops down through the central opening 59^a in the valve 50 and passes through the member 40 into the anchoring 20 tubes connected therewith and which are closed so as to form traps for the sand. The sand remains in these traps until the barrel is drawn out for cleaning.

25 The oil in its flow upwardly through the working valve when passing out into the casing 10 will be separated from any sand which may be carried thereby, the sand dropping down through the casing 10 to the bottom thereof, as shown in Fig. 3, while the 30 oil passes out in the manner above described.

When the casing 15 is raised by the pulling of the rods it will be unseated from the coupling 20 by reason of the engagement with its lower end by the head 5^a of said 35 stem thereby allowing the sand which has settled in the bottom of the casing 10 to drop down through the valve 50 and member 40 to the anchoring traps below.

In assembling the sections when the barrel 40 25 is screwed into the top of the standing valve 50 the collar 20 is simultaneously screwed into casing 30 which is possible owing to the fact that the threads are the same on these members.

45 Without further description it is thought that the features and advantages of the invention will be readily apparent to those skilled in the art, and it will of course, be understood that changes in the form, proportion and minor details of construction may be resorted to, without departing from the spirit of the invention or its scope as claimed.

I claim:—

55 1. A working barrel for oil wells comprising an outer casing composed of longitudinally aligned sections, a coupling detachably connecting said sections, a tubular valve

protector located in the upper casing section and spaced therefrom with its lower end 60 frictionally held in said coupling forming a sand collecting chamber between it and the casing, its upper end having oil outlet apertures, a working barrel in the other casing section connected with said coupling, a 65 standing valve connected with the other end of said barrel and said casing section, a valve stem extending through said protector and connected with said barrel and having means to engage said protector and unseat it on the 70 raising of the stem, a connector detachably connected with the upper end of said outer casing, a working valve connected with said stem, and means located at spaced intervals on said working valve to prevent the passage 75 of sand whereby the working members of the valve are protected.

2. A working barrel for oil wells comprising sectional inner and outer casings 80 radially spaced from each other and connected to form a sand collecting chamber between them, the inner casing having an oil outlet at its upper end and the outer casing having an oil inlet below the sand chamber, a valve stem extending through said inner 85 casing, a working valve connected with said stem, and a standing valve connected with said working valve and provided with means for separating the sand from the oil.

3. A working barrel for oil wells including a standing valve comprising a body member having means for connection with a barrel casing and a working valve, oil chambers at the top and bottom of said standing valve with passages extending through the 90 body and discharging into the bottom chamber, valved passages between the two chambers, and a bore extending through said body and connected with said top chamber.

4. A working barrel for oil wells including a connector having means for connection with the well tubing, an outer casing depending from said connector and having an apertured guide member and a coupling located therein, a tubular valve protector or 100 inner casing extending through and centered by said guide and seated in said coupling, said protector having oil outlet openings at its upper end below said guide, a 105 valve stem extending through said protector and having an enlargement to engage and unseat said protector when the stem is lifted to discharge the sand collected between said protector and outer casing above said valve.

CHARLES HEATH.
